UNITED STATES PATENT OFFICE.

PHILIP J. HELLMICH, OF PHILADELPHIA, PENNSYLVANIA, ASSIGNOR TO REUEL W. ELTON, SECRETARY OF SOCIETY KNOWN AS EIGHTIETH DIVISION, VETERANS ASSOCIATION, IN TRUST FOR SAID SOCIETY, OF PITTSBURGH, PENNSYLVANIA.

DESIGN FOR A BADGE, EMBLEM, OR AN ARTICLE OF A SIMILAR NATURE.

• 54,517.

Specification for Design.

Patented Feb. 24, 1920.

Application filed July 17, 1919. Serial No. 311,648. Term of patent 14 years.

To all whom it may concern:

Be it known that I, PHILIP J. HELLMICH, a citizen of the United States, residing in the city and county of Philadelphia, State of Pennsylvania, have invented a new, original, and ornamental Design for Badges, Emblems, or Articles of Similar Nature, of which the following is a specification, reference being had to the accompanying drawing, forming part thereof.

The figure is a face view of a badge, emblem or an article of a similar nature showing my new design.

I claim:—

The ornamental design for a badge, emblem, or an article of a similar nature as shown.

PHILIP J. HELLMICH.
